UNITED STATES PATENT OFFICE.

EMMET E. WEBB, OF CADIZ, OHIO.

CARPET-FASTENER.

SPECIFICATION forming part of Letters Patent No. 611,158, dated September 20, 1898.

Application filed March 7, 1898. Serial No. 672,989. (No model.)

To all whom it may concern:

Be it known that I, EMMET E. WEBB, a citizen of the United States, residing at Cadiz, in the county of Harrison and State of Ohio, have invented certain new and useful Improvements in Carpet Stretchers and Fasteners; and I do hereby declare the following to be a full, clear, and exact description of the invention, such as will enable others skilled in the art to which it appertains to make and use the same.

My invention relates to certain new and useful improvements in carpet-fasteners, and has for its object to provide such a device which will effectually retain the carpet in position without injury to the same.

Its further object is to make the operation of laying or removing a carpet easily and quickly accomplished.

With these and other objects in view my invention consists in the novel details of construction and combinations of parts to be more fully described in the following specification and clearly set forth in the claims.

Referring to the accompanying drawings, forming part of this specification, in which like letters of reference indicate like parts, Figure 1 is a perspective view of the side of a room, showing a strip of carpet held in place by my invention. Fig. 2 is a perspective view of a border-strip and angle-strip in engagement. Fig. 3 is a transverse section thereof. Fig. 4 is a section through a clip, showing the parts in position engaging a piece of carpet. Fig. 5 is a perspective view of a clip. Fig. 6 is a perspective view of an angle-clip.

In the drawings, A is a piece of carpet engaged at its edge by a number of border keeper-strips B, each consisting of a strip of sheet metal having one edge bent up at right angles and provided with a series of teeth C, passing through said carpet. The opposite edge of the border-strip B is bent over at an acute angle to the lower portion to form a confining flange which is provided with a series of depressions D for a purpose hereinafter explained.

An angle clamping-strip E, having sides of unequal width, is slipped within each border-strip, with its narrow side bearing against

the carpet to prevent it from sliding off the teeth. This angle-strip is retained in position by reason of its being confined within the three faces of the border-strip, as clearly shown in Fig. 3.

At intervals along the floor, close to the washboard, I have arranged sheet-metal clips F to engage the border and angle clips. Each of these clips F has a flat T-shaped portion, with perforations through which nails or the like are driven to secure it to the floor, and on the end is a spring-strip, first bent at an acute angle with the flat portion and then downward to form a hook to engage the angle-strip above the teeth, as shown in Fig. 4.

To apply my invention, the teeth of one border-strip are run through the edge of the carpet from beneath and an angle-strip slipped into position. This is repeated along the full edge of the carpet, and then the strips of two adjacent sides are forced into engagement with the clips previously arranged around the room, as shown, preferably at such distances apart that they will cover or break joint with the meeting edges of the strips, so that they appear continuous. Now the end of the loose strip nearest the attached part is engaged in the corner clip and used as a lever to draw the carpet tight while moving into its position of engagement with the other clips, and each succeeding strip is used in turn in a similar manner, thereby effectually stretching the carpet by the operation of securing it in place. The advantages of this method of laying carpets will readily be appreciated when it is considered

that no nails or tacks are driven through the carpet and no unsightly marks of a misdirected hammer-blow are made on the washboard, so common where tacks are relied on. Furthermore, there is no disfigurement to the floor which will show when the carpet is removed, the clips being rather ornamental than otherwise. This latter advantage makes my invention very desirable for use on highly-polished floors where it is often required to remove the carpet for dancing purposes and the like. With my construction the process of removing the carpet is made very simple and speedy, for it is only necessary to lift the

ends of the clips and withdraw the strips, which may be disconnected and used again on another carpet, if desired.

The angle-clips F' before referred to are clearly shown in Fig. 6 and consist of angular pieces of sheet metal having upturned edges with their ends bent downward similar to the clips. These angle-clips are adapted to be placed in corners to engage the adjoining ends of two angularly-arranged border keeper-strips B.

The depressions D in the confining-flanges of the border-strips serve to strengthen them against the upward pressure of the angle-strips caused by the pull of the carpet, and when my invention is used in connection with a rug or the like these depressions are made further useful by engaging the clips, thereby preventing longitudinal movement of the strips.

It is obvious that numerous changes can be made in the device as herein described without departing from my invention, such as turning the edges of the border-strips in curves instead of angles. In this case it is understood that the clips F would also be curved to conform therewith.

Having thus fully described my invention, what I claim as new and useful, and desire to secure by Letters Patent, is—

1. A carpet-fastener consisting of a border-strip provided at its front edge with penetrating teeth or projections and bent upwardly and forwardly at its rear end to form a confining-flange, and an angular clamping-strip adapted to be slid longitudinally between the base-plate of said border-strip and its flange

to retain the edge of the carpet in position, substantially as described.

2. A carpet-fastener consisting, essentially, of a border-strip provided at its front edge with penetrating teeth or projections and bent upwardly and forwardly at its rear end to form a confining-flange extending at an acute angle thereto, an angular clamping-strip adapted to be slid longitudinally between the base-plate of said border-strip and its flange to retain the edge of the carpet in position, and clips having spring-hooks to receive and bear upon the confining-flange and clamping-strip, substantially as described.

3. In a carpet-fastener, a strip having one side bent at an acute angle and containing a series of depressions and the other turned upward, teeth on the second-named side, an angle-strip having one side adapted to be engaged in the acute angle to hold the other in contact with the carpet, and spring-clips provided with hooked ends for securing strips to the floor, substantially as described.

4. In a carpet-fastener, strips adapted to engage the edge of the carpet, in combination with a clip formed of a T-shaped piece of sheet metal provided with a spring-strip bent upward at an acute angle and then downward forming a spring-hook to engage the strips, substantially as described.

In testimony whereof I affix my signature in presence of two witnesses.

EMMET E. WEBB.
